UNITED STATES PATENT OFFICE.

FERDINAND KRONENBERGER, OF NEW YORK, N. Y.

DESIGN FOR A TICKET-BLANK.

SPECIFICATION forming part of Design No. 31,378, dated August 8, 1899.

Application filed July 15, 1899. Serial No. 724,006. Term of patent 14 years.

To all whom it may concern:

Be it known that I, FERDINAND KRONENBERGER, of the city of New York, borough of Bronx, in the county of New York and State 5 of New York, have invented and produced a new and original Design for a Ticket-Blank, of which the following is a full, clear, and exact description.

Reference is to be had to the accompanying 10 drawings, forming part of this specification, in which—

Figure 1 is a plan view of a ticket-blank, showing my design; and Fig. 2 is a section through the line 2 2 of Fig. 1.

15 The leading feature of my design for a

ticket-blank consists in a body portion having a row of perforations extended diagonally across each of its corners. The four rows of perforations practically form a square, as shown, and arranged within the square thus ²⁰ formed is an outline panel, and within this panel is a circular row of perforations.

I claim—

The design for a ticket-blank, herein shown and described.

FERD. KRONENBERGER.
